BOW TIE

Robert D. Sherwood, Whitefish Bay, Wis.

Application April 28, 1948, Serial No. 146,003

Term of patent 3½ years

(Cl. D3—16)

To all whom it may concern:

Be it known that I, Robert D. Sherwood, a citizen of the United States and resident of Whitefish Bay, in the county of Milwaukee and State of Wisconsin, have invented a new, original, and ornamental Design for a Bow Tie, of which the following is a specification, reference being had to the accompanying drawing, forming part thereof.

Figure 1 is a front elevational view of a bow tie, showing my new design.

Figure 2 is a top plan view of the same.

Figure 3 is a rear elevational view of the bow tie.

Figure 4 is a side elevational view of the bow tie.

I claim:

The ornamental design for a bow tie, as shown.

ROBERT D. SHERWOOD.
